UNITED STATES PATENT OFFICE.

WALTER VERNON, OF COLUMBUS, OHIO.

DEVICE FOR CONNECTING HANDLES TO BRUSHES.

1,166,280.

Specification of Letters Patent. Patented Dec. 28, 1915.

Application filed July 7, 1915. Serial No. 38,456.

To all whom it may concern:

Be it known that I, WALTER VERNON, a citizen of the United States, residing at Columbus, in the county of Franklin and 5 State of Ohio, have invented new and useful Improvements in Devices for Connecting Handles to Brushes, of which the following is a specification.

This invention relates to improvements in 10 connecting devices for brush handles and has particular application to a device for effecting a detachable connection between the brush and the handle.

In carrying out the present invention, 15 it is my purpose to provide a device of the class described whereby a handle may be readily and quickly applied to a hand brush and removed therefrom so that the brush may be operated with ease and facility.

20 It is also my purpose to provide a device of the type set forth which will embrace the desired features of simplicity, efficiency and durability, which may be readily and conveniently put into use and wherein the component parts will be so arranged and correlated as to reduce the possibility of derangement to a minimum.

With the above and other objects in view, the invention consists in the construction, 30 combination and arrangement of parts hereinafter set forth in and falling within the scope of the claim.

In the accompanying drawing; Figure 1 is a perspective view of a brush and handle 35 connected together by means of a device constructed in accordance with the present invention. Fig. 2 is a similar view of the device removed from the brush.

Referring now to the drawing in detail, 40 1 designates a brush of any suitable or preferred construction embodying a head 2 and bristles 3.

4 designates a handle, while 5 indicates my improved connecting device as an entirety. This device comprises a head bar 6 having one edge formed with outwardly 45 projecting lugs 7 spaced apart in parallelism and having the outer ends thereof equipped with downwardly projecting arms 8, respectively, the lower ends of the arms being formed with inturned bills 9 lying 50 parallel with the lugs 7. Formed on the edge of the head bar 6 between the lugs 7

and arranged at any desired angle relatively to the head bar is a sleeve 10 that 55 receives one end of the handle 4 and formed on the sleeve 10, and projecting outwardly therefrom at diametrically opposite points, are studs 11.

12 designates a lever which, in the present 60 instance, is formed of a single length of wire bent upon itself between its ends as at 13 and having the limbs thereof offset from the bent portion 13 as at 14 and formed with loops 15 adjacent to the extremities thereof and eyes 16 at the extremities. The eyes 16 receive the studs 11 and the limbs of the lever are designed to lie upon opposite sides of the handle, while that portion of the lever between the bend 70 13 and the offset portions 14 embraces the handle.

17 designates a clamp. In the present 75 instance, this clamp is constructed from a single length of wire formed to provide a bar 18, legs 19 projecting outwardly from the bar at right angles thereto and offset outwardly therefrom, coiled retractile springs 20 contiguous to the ends of the legs 19, and eyes 21 at the outer ends of the springs 80 20. The eyes 21 engage in the loops 15 in the offset limbs 14 of the lever 12.

In practice, one end of the handle 4 is secured in the sleeve 10 and the head bar 6 is placed upon the upper surface of the 85 head 2 of the brush, while the lugs 7, arms 8 and bills 9 embrace the adjacent edge of the brush. The bar 18 and legs 19 of the clamp 17 are now engaged with the opposite edge of the brush and the lever 12 90 swung toward the handle and in the swinging of the lever the loops 15 pass to the opposite side of the fulcrum point of the lever, thereby locking the clamp and the head to the brush, the springs 20 being 95 tensioned to maintain the connection between the handle and the brush.

While I have herein shown and described one preferred form of my invention by way of illustration, I wish it to be understood 100 that I do not limit or confine myself to the precise details of construction herein described and delineated, as modification and variation may be made within the scope 105 of the claim without departing from the spirit of the invention.

1,166,280

I claim:

A detachable connection for connecting a brush and a handle, said connection comprising a head bar connected to one edge of the brush, a clamp adapted to engage the opposite edge of the brush, a lever for drawing said head bar and clamp together, a connection between said lever and head

bar, and a yieldable connection between said lever and clamp.

In testimony whereof I affix my signature ¹⁰ in presence of two witnesses.

WALTER VERNON.
